A technical drawing of a component labeled '10'. It features a rectangular frame with a vertical slot on the left side and a horizontal slot on the right side. A reference line labeled '21' points to the left side of the vertical slot. A reference character labeled '2' is located to the right of the horizontal slot.

UNITED STATES PATENT OFFICE.

EMIL BERTA, OF JOLIET, ILLINOIS.

WRENCH.

Application filed June 4, 1926. Serial No. 113,697.

This invention relates to new and useful improvements in wrenches for pipes, nuts and the like, and has for its object to provide a wrench that is self-adjustable and self-releasable and for this reason may be quickly adjusted to pipes, nuts or other articles of varying size and quickly released from the article when desired.

A further object of my invention is to provide a wrench of this character that is very economical in cost and highly efficient, practical, and durable in use.

With the foregoing and other objects in view that will appear as the nature of my invention is better understood, the same consists in the novel features of construction, combination and arrangement of parts illustrated in the accompanying drawings and more particularly pointed out in the appended claim.

In the accompanying drawings, which are for illustrative purposes only and are therefore not drawn to scale:

Figure 1 is a side elevation of a wrench embodying my improvements, the jaws closed.

Figure 2 is a similar view, the jaws open.

Figure 3 is a plan view of Figure 1.

Figure 4 is a central longitudinal section 30 of Figure 1.

Figure 5 is a vertical transverse section, taken on line 5-5 of Figure 4 and looking in the direction indicated by the arrows.

Figure 6 is a horizontal section, taken on line 6-6 of Figure 4.

Figure 7 is a vertical transverse section, taken on line 7-7 of Figure 1, looking in the direction indicated by the arrows.

Figure 8 is a similar view, taken on line 40 8-8 of Figure 1.

Figure 9 is a detailed perspective view of the fixed or stationary jaw.

Figure 10 is a similar view of the movable jaw.

Figure 11 is a detailed fragmentary perspective view of the frame bar.

Figure 12 is a similar view of the movable jaw carrying sleeve or member and Figures 13 and 14 are detail side views of a modified 50 form of the fixed and movable jaws, respectively.

Referring to the drawings for a more particular description of my invention and in which drawings like parts are designated by like reference characters throughout the several views, my wrench essentially com-

prises a fixed jaw 1, a movable jaw 2, a horizontal frame bar 3 to which the fixed jaw is fastened, a longitudinally movable sleeve 4 which carries the movable jaw 2, 60 and the operating handle 5.

In carrying out my invention, the front end of the frame bar 3 is recessed or cut-away, as at 6, and the fixed jaw provided at its inner end with an off-set portion 7 65 which is secured to the recessed front end of the frame bar 3 by the transverse fastening screws 8 or other equivalent means. The sleeve 4 is mounted to slide back and forth over the frame bar 3 and is formed at its 70 front or outer end with an enlarged substantially square head or socket 9 to snugly receive a substantially square hollow head 10 formed at the inner end of the movable jaw 2. The head 10 is fastened in the socket 75 9 by the transverse screws 11 or other equivalent means. As shown, the inner or rear end of the frame bar 3 is provided with an arm 12 which extends upwardly and rearwardly at an angle of approximately 45 80 degrees and to the upper end of which is pivoted or fulcrumed, as at 13, the operating handle 5. The lower end of handle 5 is provided with a depending forwardly inclined fork 15, the lower ends of whose tines 85 or members straddle the inner or rear ends of the side members of the sleeve 4 and are loosely and pivotally connected therewith by the slot and bolt connection 18 and 19 or other equivalent means.

In practice, the jaws 1 and 2 may be spread apart by the simple expedient of pulling upwardly on the handle 5, as illustrated in Figure 2 and may be quickly and readily engaged with the pipe, nut or other article 95 by pressing down on the handle 5, which causes the movable jaw and sleeve to slide forwardly on the frame bar 3. If desired, the inner or gripping edges of the fixed and movable jaws may be formed with teeth or 100 serrations 20 and 21, respectively, in order to more securely engage or grip the article.

From the foregoing description taken in connection with the drawings it is thought that the construction, operation and advantages of my invention will be readily understood without requiring a more extended explanation.

Having described my invention, what I claim as new and desire to secure by Letters 110 Patent, is:

In a device of the character specified, a

frame bar, a fixed or stationary jaw secured to the front end of said frame bar, a sleeve slidably mounted on said bar, a movable jaw carried by the front end of said sleeve, 5 an arm extending upwardly and rearwardly from the frame bar, a handle pivoted to said arm and provided with a depending forwardly inclined fork and a slot and bolt connection for loosely and pivotally connecting the fork with the sleeve. In testimony whereof he affixes his signature. 10

EMIL BERTA.
